UNITED STATES PATENT OFFICE.

LOUIS A. SUEKOFF, OF CHICAGO, ILLINOIS.

SPRING-CUSHION CONSTRUCTION.

1,410,965.

Specification of Letters Patent. Patented Mar. 28, 1922.

Original application filed January 30, 1919, Serial No. 273,957. Divided and this application filed June 11, 1920. Serial No. 388,107.

To all whom it may concern:

Be it known that I, LOUIS A. SUEKOFF, a citizen of the United States, residing at Chicago, in the county of Cook and State of Illinois, have invented certain new and useful Improvements in Spring-Cushion Constructions, of which the following is a specification.

This invention relates to improvements in 10 spring cushion constructions adapted for incorporation in seat and mattress structures, and the present application is a division of my former application which was issued as Letters Patent of the United States No. 15 1,397,021, dated November 15, 1921.

The object of the present invention is to provide a construction of this character wherein maximum economy may be effected in the amount of materials employed when 20 producing the same.

Furthermore, the invention also contemplates the provision of a novel form and arrangement of the spring units and their envelopes, whereby but a single ply of material 25 is present between contiguous springs, thus eliminating unnecessary use of the fabric of the envelopes and at the same time providing the requisite separation of the springs to prevent their contact with each other. 30 The sound of the springs in their relative movement with respect to each other is thereby precluded, while material saving in the textile fabric of the envelopes or covering for the springs is effected.

35 Other objects and advantages will appear as the nature of the improvements is better understood, the invention consisting substantially in the novel construction, combination and arrangement of parts hereinafter fully 40 described, illustrated in the accompanying drawings, and finally pointed out in the appended claims.

In the drawings—

45 Fig. 1 is a top plan view of the herein-described invention, the springs being illustrated in dotted lines.

Fig. 2 is a detail vertical transverse sectional view on the line 2—2, Fig. 1.

50 Fig. 3 is a similar view on the line 3—3, Fig. 1.

Fig. 4 is a detail perspective view of the envelopes, broken away, for one series of the springs.

Referring now in detail to the accompany-

ing drawings, it will be observed that the 55 herein-described spring cushion construction is made up of a plurality of individual springs properly separated from each other to prevent contact of the several springs so that they may move independently, and likewise 60 without the metallic sound that emanates from the rubbing action of their coils upon each other. It includes a plurality of independent unitary envelopes or pockets, each spring having its individual envelope or 65 pocket, as most clearly illustrated in Fig. 4. Each of these pockets is formed of a single strip of material 10 which includes vertical side walls 11, a bottom 12, and a top 13, and the ends of said strip, which ends are the 70 terminal portions of one of the side walls 11 and the top 13, are connected, as at 14, as by stitching or equivalent fastening means. A spring 15 occupies each of the envelopes or 75 pockets, and the expansive force of said springs exerts stretching action upon the pocket or envelope so that the side walls thereof are properly tensioned. In assembling these envelopes or pockets they are so arranged that each of the envelopes or pockets is disposed at right angles to the envelopes contiguous thereto, which arrangement is clearly illustrated in Fig. 4. In this manner the side walls 11 serve to close the open 80 portions of the envelopes of contiguous pockets, and the ends of the several pockets are fastened together along their marginal portions 16, as by stitching or equivalent fastening means, thereby uniting the several envelopes or pockets into an integral structure. 90

In uniting the several pockets in the manner above described it will be understood that the cushion construction may be extended to any desired dimension. A single ply 95 only of the material is employed for each of the pockets, and at each side thereof, and by disposing the contiguous pockets at right angles to each other economy of material is effected, due to the open sides of each pocket being closed by the material of the adjacent 100 pockets located at right angles thereto. The springs are prevented contacting with each other so that their relative movement may be had without the coils of contiguous springs being brought together or rubbing directly 105 against each other. Inasmuch as the walls of the pockets are connected only at their top and bottom marginal portions, the inter-

mediate edges being free, access may be readily had to each individual pocket for inserting the springs into and removing the same therefrom.

5 I claim:

1. A spring cushion construction of the class described, comprising a plurality of independent unitary envelopes or pockets each of which is arranged at right angles to the adjacent pockets, two of the opposite sides of each of said pockets being open, and a spring arranged within each of said pockets, the open sides of each of said pockets being closed by the closed sides of the pockets contiguous thereto, the ends of the several pockets being connected along their marginal portions to unite the pockets into an integral structure.
2. A spring cushion construction of the class described, comprising a plurality of independent unitary envelopes or pockets each

of which is formed of a strip of material connected at its ends and including vertical side walls, a top, and a bottom, the opposite sides of each of said pockets being open, and a spring arranged in each of said pockets, each pocket being arranged at right angles to the adjacent pockets, whereby the vertical side walls of each pocket serve to close the open sides of the adjacent pockets, said vertical side walls separating the respective springs from contact with each other, the ends of the several pockets being connected along their marginal portions to unite the pockets into an integral structure.

In testimony whereof I have hereunto signed my name in the presence of two subscribing witnesses.

LOUIS A. SUEKOFF.
